[57] CLAIM

The ornamental design for a fish box, as shown and described.

DESCRIPTION

FIG. 1 is a front elevational view of a fish box showing my new design, the rear elevational view being identical thereto;

FIG. 2 is a side elevational view, the opposite side being identical thereto;

FIG. 3 is a top plan view thereof;

FIG. 4 is a bottom plan view thereof;

FIG. 5 is a perspective view showing the design from above; and

FIG. 6 is a perspective view showing the design from underneath.

FIG. 1

FIG. 2

FIG. 5

FIG. 6
